Harold R. Owen, Venice, Calif., assignor to Electrical Products Corporation, Los Angeles, Calif., a corporation of California

Application April 8, 1941, Serial No. 100,219

Term of patent 7 years

To all whom it may concern:

Be it known that I, Harold R. Owen, a citizen of the United States, residing at Venice, in the county of Los Angeles and State of California, have invented a new, original, and ornamental Design for a Cap Piece for a Sign, of which the following is a specification, reference being had to the accompanying drawing, forming part thereof.

Fig. 1 is an end view of a cap piece for a sign showing my new design;

Fig. 2 is a side elevational view thereof;

Fig. 3 is a plan view thereof; and

Fig. 4 is a perspective view thereof.

I claim:

The ornamental design for a cap piece for a sign, as shown.

HAROLD R. OWEN.
